UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

OIL SWITCH AND CONTROLLING MECHANISM.

Application filed September 2, 1922. Serial No. 585,879.

My invention relates to circuit interrupters having relatively movable contact members immersed in a fluid, and more particularly to the mechanism for operating the contact members.

One object of my invention is to provide an operating mechanism for large-capacity circuit interrupters which is designed to securely hold the contact members during the severe "blowout" forces incident to the interruption of electrical currents of great magnitude.

Another object of my invention is to provide an operating mechanism for circuit interrupters which shall be quick and positive in its operation.

A further object of my invention is to provide an operating mechanism for circuit interrupters which shall be simple in construction and consist of few parts.

I have found that the "blowout" forces, both electrical and chemical, incidental to the interruption of an electrical circuit carrying a large current at a high voltage, to be so severe as to require greater strengthening and bracing of the supporting rods carrying the movable contact member than is found in the mechanisms heretofore constructed.

In accordance with my invention, a guide member is rigidly secured to an inner wall of the receptacle enclosing the circuit-interrupting mechanism. A pair of movable supporting rods are arranged to move parallel with, and adjacent to, said guide members, thereby receiving additional support. The movable contact member is secured to both supporting members, thereby giving the contact member greater resistance to bending moments and securing a simultaneous break from both of the fixed contact members.

A plurality of supporting rods are secured to the movable contact member at spaced points. The supporting rods are suspended from a common member which is pivotally supported by a train of link mechanism. The supporting rods are secured to a guide post in such a manner that they are braced a short distance from their connection to the movable contact member.

Because of the comparatively short un-

supported portions of the supporting rods and because of the existence of a plurality of fixed bearing points on the moving contact member, twisting and bending of these parts is reduced to a minimum.

In the several views of an embodiment of my invention:

Figure 1 is a sectional view of a circuit interrupter showing the position of the controlling mechanism when the contact members are in a closed position.

Fig. 2 is a similar view illustrating the position of the controlling mechanism when the contact members are in a semi-open position.

Fig. 3 is a similar view illustrating the position of the controlling mechanism when the contact members are in their open position.

Fig. 4 is a view, partially in section and partially in elevation, of a circuit interrupter equipped with my invention.

Fig. 5 is a side view of the link mechanism taken along the line IV—IV of Fig. 3.

In the several figures of the drawing, similar reference numerals refer to like parts.

In Fig. 4 is shown a circuit interrupter 1, of any desired form, comprising a tank portion 2 and a cap portion 3. In practice, the tank 3 is filled with a fluid (not shown). Secured to the cap 3 are a pair of insulators 4 and a housing 5 for the control mechanism to be hereinafter described. In case a polyphase circuit interrupter be desired, a corresponding number of insulators 4 may be provided.

In the tank 2, a pair of fixed contact members 6 constitute the terminals for the conductors entering the interrupter through the insulators 4. A movable contact member 7, having contacts 8 mounted thereon in registry with contacts 6, is supported by a plurality of supporting rods 9, of any suitable material, as, for example, insulated iron piping, wood or micarta.

A guide member 11, of any suitable material, is mounted on the cap member 3 by means of a bracket 12, clamping bolts 13, straps 14 and clamp 15. A brace 16 (Fig. 4) serves to hold the rods 9 in their proper spaced relation to guide 11, as well as to brace said rods.

Secured to the cap 3 are a series of aligned conduits 17, 18 housing a control rod 19. In the arrangement here illustrated, rod 19 extends to a plurality of circuit interrupters 5 for simultaneous operation thereof. It is obvious that the length of the rod 19 may be changed for any other desired number of interrupters.

A suitable fitting 21 is attached to rod 19. 10 A rocker arm 22 is pivoted, as at 23, to the fitting 21. One end of arm 22 is pivoted, as at 24, to the bracket 12 and straps 14. The opposite end of arm 22 is provided with a head 24 for contact with a spring 25 that is mounted, by means of a bracket 26, upon cap 3. A link 27 is pivoted to the arm 22, as at 28, adjacent to the head 24.

Pivoted between straps 14, as at 29, is a slotted bracing link 31 pivotally secured to 20 link 27, as at 32. A bracket 33 is rigidly secured to bracket 26. Pivoted, as at 34, to bracket 33, are a pair of links 35 which are, in turn, pivoted, as at 36, to a heavy bifurcated member 37.

25 As shown in Fig. 5, member 37, is a specially braced link of H-shape, the ends of which terminate in bifurcations 38, 39. Ends 39 are further bifurcated to form ears for pivots 36, and ends 39 are further bifurcated for attachment of the supporting rods 9 by fitting 40. Substantially midway of its length, member 37 is attached to link 31 by the pivot 41.

The operation of the link mechanism is best understood by following the movement of each part from the closed positions of the contact members 6, 7 and 8, as shown in Fig. 1, to their open positions, as shown in Fig. 3, Fig. 2 illustrating their intermediate 40 positions.

To open the contact members rod 19 is actuated, in any desired manner, toward the right, (Fig. 1) with a corresponding movement of the pivot point 23. After a very short movement of rod 19, rocker arm 22 passes the dead-center line between pivots 23 and 24, after which the movement of the parts is accelerated by the force of gravity and by the arc "blowout" forces.

50 Movement of arm 22 causes link 27 to bear upon link 31, and the latter, turning about point 29, draws upon link member 37. The latter has a pivotal movement about point 36, as well as a translatory motion caused by the turning of links 35 about point 34. The result is to effect a substantially rectilinear movement of the upper end of the link 37 and the rod 9 connected thereto.

The rods 9 are guided by the members 11 60 and 16 so that an even break is made between both sets of contacts 6, 8, without bending or twisting of member 7.

The downward movement of the parts is terminated when head 24 strikes spring 25,

the latter acting as a shock absorber for the 65 entire system.

To close the contact members, rod 19 is moved to the left, Fig. 3, which, in turn, causes the parts to assume the position shown in Fig. 1.

70 It will thus be seen that I have devised a quick positive-acting control mechanism which is rugged in construction and yet simple to manufacture.

75 While I have shown and described a particular form of my invention, changes may be effected therein without departing from the spirit and scope thereof, as set forth in the appended claims.

I claim as my invention:

1. In a circuit interrupter, a pair of fixed contact members, a movable contact member adapted to bridge said fixed contact members, a plurality of spaced supporting members secured directly to said movable contact member and disposed in a longitudinal plane thereof, and a series of links for controlling said supporting members.

2. In a circuit interrupter, a pair of fixed contact members, a fixed guide member extending between said fixed contact members, a movable contact member bridging said fixed contact members, a pair of supporting members attached to said movable contact member at such a distance from the guide member as to prevent twisting of the bridging member, said guide member being disposed between said supporting members and in a longitudinal plane thereof, and a link-work for controlling said supporting members.

3. In a circuit interrupter, a movable contact member, a pair of spaced supporting rods secured directly to said contact member, a bifurcated floating member for connecting said supporting rods in spaced relation, and mechanism for actuating the bifurcated member.

4. In a circuit interrupter, an actuating means, a link controlled by said actuating means, one end of said link being pivotally connected to the circuit-breaker frame, a second link secured to the free end of the first named link, a third link pivoted to the circuit-breaker frame and controlled by the second named link, a bracket member secured to the circuit-breaker frame, a fourth link secured to an end of said bracket member, a bifurcated member supported by the fourth-named link, said bifurcated member being actuated by movement of the third-named link, a movable contact member, and supporting rods for said movable contact member supported by said bifurcated member.

5. In a circuit interrupter, a fixed guide member, a movable contact member, a plurality of supporting rods associated with

- said guide member and disposed on opposite sides thereof in a longitudinal plane of the contact member for moving said contact member and link mechanism for actuating 5 said supporting rods.
6. In a circuit interrupter, the combination with a pair of fixed contact members and a movable contact member spanning said fixed contact members, of a plurality 10 of supporting members secured at spaced intervals to said movable contact member in a longitudinal plane thereof whereby bending and twisting of the latter is prevented.
- 15 7. In a circuit-interrupter mechanism, a contact bridging member, a pivoted member, a plurality of contact-supporting members, suspended therefrom and connected to the bridging member in a longitudinal plane
- thereof, and means for actuating said pivoted member.
8. In a circuit breaker, a bridging member, a pair of supporting rods directly connected thereto in spaced relation and in a longitudinal plane thereof, a floating lever 25 for actuating the rods, pivotally supported at one end by a pair of relatively widely-spaced supporting members having their pivot shaft disposed parallel to the plane of the rods, and pivotally engaging the said rods at relatively widely separated points, to constitute a pivotal linkage capable of resisting side stresses without appreciable deflection.
- In testimony whereof, I have hereunto 30 subscribed my name this 31st day of August, 1922.

CHRISTIAN AALBORG.
